UNITED STATES PATENT OFFICE

MERCIE IVORY AND THOMAS W. ALLRED, OF NEPHI, UTAH

URINAL

Application filed September 25, 1929. Serial No. 395,083.

This invention relates broadly to medical appliances, and has more particular reference to devices especially adapted for use by bed ridden patients.

5 The primary object of the invention is to provide a urinal especially adapted for use by a bed ridden patient, the device being substantially triangular in cross-section, the sides and end walls of the container at their upper ends merging into an elongated tubular neck closed at one end and open at its opposite end to provide a single filling opening for the receptacle.

A still further object of the invention is 15 to provide a device of this nature, which is simple in construction, practical, which can be used without inconvenience, and wherein the liability of spilling the contents of the container will be reduced to a minimum.

20 Other objects and advantages of the invention will become apparent during a study of the following description taken in connection with the accompanying drawings, wherein:

25 Figure 1 is a perspective view of the device constructed in accordance with the present invention.

Figure 2 is a vertical longitudinal sectional view taken thereto.

30 With reference more in detail to the drawing, it will be seen that the urinal is designated generally by the reference character 5, the same comprising a relatively broad transversely curved bottom wall 6, and substantially triangular front and rear walls 7 and 8, respectively. The side walls 9 of the container curve inwardly and upwardly from the longitudinal edges of the bottom wall 6 toward the apices of the front and 35 the rear walls, respectively, said side walls 9 at their upper edges merging into an elongated tubular neck 10, which neck 10 inclines rearwardly from the top to the bottom of the container. The neck 10 ex- 40 tends longitudinally from the rear wall 8,

to the front wall 7, and at its rear end is closed, the rear wall 8 at its apex being extended as at 11 for closing said neck at said end. Throughout the major part of its longitudinal length, the neck 10 communicates with the interior of the container, however, the front wall 7 gradually thickens longitudinally towards its apex as at 12 forming a bottom 13 for the neck 10 of the forward end of the neck. At its forward 55 end the neck 10 is open as at 14 constituting a filling opening for the container.

The bottom wall 6 of the container is provided with a drain opening 15 and a plug 16 is threaded in the opening for closing 60 the same.

It is to be noted that at the apex thereof the front wall 7 which is thickened at its apex has the thickened portion extending laterally so that the opened end of the tube 65 10 extends laterally of the front end of the container.

It will be readily appreciated, that in view of the slight inclination of the tube 10 the matter discharged therethrough will be 70 directed to the bottom of the container, while the curved side walls of the container will permit of the patient to use the same in any one of several positions without interference with the comfort of the patient. Likewise, in view of the wide base, curved sides, the top of the container is relatively narrow, thus eliminating the danger of the container being easily tipped over, and if when used, the patient may be reclining on his 75 side, the large bottom will suffice for the usual quantity of contents without spilling. Again, as a further advantage of a device constructed as herein illustrated and described, there is but a single chamber for 80 receiving the contents by reason of which the container may be thoroughly flushed or 85 cleansed.

From the foregoing, it is apparent that a urinal embodying such features as herein 90

pointed out will greatly enhance the possibility and utility of a device of this nature.

Even though we have herein shown and described the preferred embodiment of our invention, it is to be understood that the same is susceptible to changes fully comprehended by the spirit of the invention as herein described, and the scope of the appended claims.

Having thus described our invention, what we wish to claim as new is:—

1. In a device of the class described, a portable container having a relatively broad bottom and a narrow top, the walls of said container at the top merging into a tubular neck extending longitudinally of the container, said neck being closed at one end and opened at its opposite end, and the side walls of said container curving inwardly and upwardly from the bottom to the top. 80

2. In a device of the character described, a container having a relatively broad bottom and a narrow top, the side walls of said container curving inwardly and upwardly from the bottom to the top, said side walls at their top merging into a longitudinally extending elongated tubular neck, said neck being closed at one and open at its opposite end, and the front wall of the container at the top thereof being relatively thickened and providing a bottom wall for the opened end of said neck, said front wall having an inwardly and downwardly inclined surface, and the rear wall of the container being extended to provide an end wall for the closed end of said neck. 85

3. In a device of the class described, a container having a relatively broad bottom and a narrow top, the side walls of said container curving inwardly and upwardly from the bottom to the top, said side walls at their top merging into a longitudinally extending elongated tubular neck, said neck being closed at one end and open at its opposite end, and the front wall of the container at the top thereof being relatively thickened and providing a bottom wall for the opened end of said neck, said front wall having an inwardly and downwardly inclined surface, and the rear wall of the container being extended to provide an end wall for the closed end of said neck, and the bottom wall of said container being provided with a drain outlet opening and a plug threaded in said opening. 90

4. In a device of the class described, a portable container comprising a relatively broad bottom wall, substantially triangular end walls rising from said bottom wall, said end walls being substantially triangular and having their opposite side edges curving inwardly and upwardly, side walls curving inwardly and upwardly from said bottom walls, to the apex of said end walls, said side and end walls at the top thereof 95

merging into an elongated tubular neck inclining rearwardly from one end wall to the other, said neck being open at one end and closed at its opposite end, the bottom wall of said container being provided with a drain outlet, and a plug normally closing said outlet opening. 100

In testimony whereof we affix our signatures.

MRS. MERCIE IVORY.
